UNITED STATES PATENT OFFICE.

WILLIAM GILBERT ARMITAGE, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

UNCOUPLING DEVICE.

1,097,963.

Specification of Letters Patent. Patented May 26, 1914.

Application filed February 25, 1913. Serial No. 750,549.

To all whom it may concern:

Be it known that I, WILLIAM GILBERT ARMITAGE, residing at St. Louis, Missouri, and being a citizen of the United States, have invented certain new and useful Improvements in Uncoupling Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a composite view including a plan view looking down on one-half of the end portion of the underframe of a car equipped with a preferred embodiment of my invention and showing a portion of the other half in horizontal section through a center sill. Fig. 2 is a vertical sectional view through the coupler head taken substantially on a plane indicated by the line 2—2 of Fig. 1, and showing substantially one-half of the end sill and attached parts in front elevation, and Fig. 3 is a horizontal, vertical, sectional view taken approximately on the line 3—3 of Fig. 2, parts being broken away to show the remote draft or center sill in side elevation.

My invention relates to an uncoupling mechanism to actuate the uncoupling pin or locking device in a car coupler, and it is an object of my invention to provide an actuating mechanism in the above class operable from the side of the car and which will allow free movement of the coupler without communication with any parts which might injure the operator, and the invention has for a further object the disposition of as much of the actuating parts as possible in protected position so as not to interfere with devices positioned in front of the end sill.

The invention further comprises a simple and economical arrangement of a minimum number of parts which are actuated by a positive pull on the same from a position of safety with a minimum amount of lost motion.

I attain the above outlined objects broadly by means of an arm extending from the side of the car inwardly toward the coupler and

connecting this arm to the unlocking operating lever of the coupler by means of a loose positive connecting mechanism, including a link sliding with the coupler and slidably and pivotally connected to a crank actuated by the arm.

As a vehicle for the disclosure of my invention I have shown a conventional form of underframe end, comprising spaced draft sills A, side sills B and an end sill C. Mounted on the end sill in their usual places are the push pole pocket plates D and depending striking casting E, and there is also shown a lay down brake mast.

Housed within the striking casting E and supported from the carry iron G, forming the bottom of the casting E, is a coupler H, the rear portion of which extends between the draft sills and is operatively connected with some conventional form of draft gear, and the invention as hereinafter defined is particularly applicable to those couplers having a material travel such as characterize friction draft gears of the Cardwell type.

The invention pertains to that type of coupler in which the knuckle 5 is unlocked by the actuation of a pin lifter lever 6, but as the particular form of coupler forms no part of this disclosure, a detailed description is unnecessary. With this type of coupler the lever 6, which is pivoted to the underside of the coupler head 7, moves in a plane transversely of the length of the coupler to enter the pocket 8 in the coupler head. This coupler head is, of course, normally positioned some material distance in advance of the end sills, and any direct connection extending from the lever 6 to the car side would take up space and interfere with the brakeman getting between the cars to center the coupler. To eliminate this objection and to insure sufficient room for the movement of the lay down brake shaft F in front of the end sill, the device is actuated from a transversely disposed pull arm 10 positioned to the rear of the end sill C, as shown in Fig. 3. This arm 10 is shown to have a down-turned end forming a handle 11, normally positioned as shown in full lines in Fig. 2, a slight distance to the outside of the side sill B on the side of the coupler opposite the side to which the lever 6 is pivoted, from which sill the arm is supported by a U-strap 12. The arm 10 is bent downwardly toward the center of the car to

111

- fully clear the coupler and draft sills and to be always below the double crank 13, hereinafter more fully described, in all positions of the same.
5. The actuating arm 10 is connected with the arm 14 of the operating lever 6 in such a way that there will be a positive and directly acting force controlling the movement of the lever 6, and a particular feature 10 of this invention is the connecting of those members so as to permit free movement of the coupler without moving the pull arm 10 in a manner or to an extent to affect the internal coupling mechanism within the coupler head. For this purpose a double crank 13 has its crotch 15 pivotally mounted in a bracket 16 fixed to the upper side of the lower flange of the draft sill adjacent the arm 14.
20. Forming the pivot arms of the double crank 13 are the longitudinally extending alined shafts 17 and 18, the shaft 17 being pivotally mounted in the looped end 19 of the arm 10, which engages the same below 25 the bracket 16. The shaft 18 parallels the coupler in its normal position and extends forwardly of the end sill C a distance at least as great as the maximum longitudinal travel of the coupler. Slidably mounted 30 upon the shaft 18 is the looped end 20 of a Z-shaped link 21, the opposite and forward end of which is formed into a hook 22, which engages in an eye 23 in the arm of the operating lever 6. By means of this connection 35 it will be seen that the coupler is free to move either longitudinally or to swing transversely of itself, the link 21 merely sliding or rotating on the shaft 18, and yet irrespective of the position of the coupler the 40 operator can draw the handle 11 outwardly until the parts take the position shown in dot and dash lines of Fig. 2, which action will quickly and positively swing the crank 13, thereby pushing on the link 21 to actuate the lever 6. The weight of the lever 6 and supporting parts will tend to reset the device as shown in full line position in the 45 several figures.
- What I claim is,
50. 1. In a car having a draft sill, the combination with a coupler having internal coupling mechanism, and an unlocking operating lever therefor, of a crank pivoted in fixed position upon said draft sill, a vertically rockable pull arm extending from the car side toward the coupler, and a link connecting said lever with said crank and mounted thereon to slide parallel to the axis thereof.
55. 2. In a car, a draft sill, an end sill, a coupler lapping said end sill and having a head disposed in advance of said end sill and containing internal coupling mechanism, a transversely disposed unlocking lever suspended from said head for actuating said coupling mechanism, a transversely disposed vertically rockable bent pull arm positioned in rear of said end sill, a pivoted crank attached to said draft sill, and a link mounted on said crank to slide parallel to the axis thereof, pivotally connecting said crank with said unlocking lever.
3. In a car provided with draft sills, the combination with a coupler having internal coupling mechanism and an uncoupling lever therefor pivoted to said coupler, of a crank shaft attached to one of said draft sills, and a link mounted on said shaft to slide parallel to the axis thereof and being pivotally connected to said lever.
4. In a car, the combination with a coupler having longitudinal and transverse movement and having an unlocking device carried thereby, of a transverse pull arm rendered operable by an outward pull thereof, a link pivoted to said unlocking device, and means connecting said link and said pull arm, said means being rockable in a bearing held in fixed position and said link having a pivotal and slidable connection with said means.
5. In a car having an underframe, the combination of a coupler having an unlocking mechanism carried thereby and capable of longitudinal and swiveling movement relative to the car, of a double crank mounted on the underframe of said car and rendered operable by a pull on one arm thereof, and means intermediate of said crank and said unlocking mechanism pivotally connected to each and mounted to slide longitudinally on said crank.
6. In a car, the combination of a coupler having an unlocking mechanism carried thereby and capable of longitudinal and swiveling movement relative to the car, of a crank mounted independently of and adapted to rock independently of said coupler, means intermediate said shaft and said unlocking mechanism pivotally connected to each and mounted to slide longitudinally on said crank and means for actuating said crank to operate said unlocking mechanism.
7. In a car, having an end and draft sills, the combination with a coupler having internal coupling mechanism and a transversely disposed unlocking mechanism therefor, of a vertically rockable pull arm having a downwardly bent portion, and being transversely disposed at the rear of said end sill, a double crank pivotally mounted on one of said draft sills, and a link pivotally mounted on the outer arm of said crank and pivotally connected to said unlocking mechanism, said link being slidable parallel to the axis of said crank.
8. In a car, having an end sill and draft sills, the combination with a coupler having internal coupling mechanism and carrying

ing a transversely disposed unlocking lever therefor, of a vertically rockable pull arm having a downwardly bent portion, and being disposed at the rear of and parallel to said end sill, a double arm crank pivotally mounted on one of said draft sills and extending substantially parallel thereto, a link pivotally mounted on the outer arm of said crank and slidably thereon parallel to the axis thereof, said link being pivotally connected to said unlocking lever and extending substantially parallel to said pull arm.

9. In a car, having an end sill and draft sills, the combination with a coupler carrying a suspended unlocking lever, said coupler being capable of longitudinal and transverse movement, of a pull arm disposed at the rear of and parallel to said end sill and

extending from outside of the car frame inwardly to a point beyond the draft sills, a 20 double arm crank pivotally connected to said pull arm and pivotally supported by and extending substantially parallel to said draft sills, a link pivotally and slidably mounted on the outer arm of said crank and 25 disposed substantially parallel to said pull arm, said link being bent forwardly and rebent into a plane parallel to said pull arm and being pivotally connected to said unlocking lever.

30

In witness whereof I have hereunto set my hand in the presence of two witnesses.
